VOLTAGE AND CURRENT REGULATOR**Henry M. Huge, Bay Village, Ohio, assignor to Lorain Products Corporation, a corporation of Ohio****Application July 30, 1953, Serial No. 371,225****13 Claims. (Cl. 321—25)**

This invention deals with a voltage and current regulating device, and more particularly with a device in which a rectified output voltage is closely regulated, under the control of a biasing current. My invention employs saturating magnetic cores having impedance windings which regulate the flow of rectified current and saturating windings energized in part by load current and in part by current from a source of uni-directional bias. As a source of constant bias current, in one embodiment of my invention I employ a voltage regulating circuit which is not sensitive to variations in input frequency nor input voltage, and which delivers a constant rectified current to the saturating winding even though the resistance of the winding may change with changes in temperature.

It is an object of my invention to provide a source of precisely regulated rectified voltage whose potential is not affected by changes in alternating current input voltage, input frequency, ambient temperature, or load current.

Another object of my invention is to provide a source of regulated direct current especially suited for use as a standard voltage source in a larger control system.

Another object of my invention is to provide a source of regulated direct voltage having an easily adjustable internal negative resistance characteristic, so that a constant voltage can be maintained across a load which is fed from the regulating device through a series resistance.

An additional object of my invention is to connect a control device between a source of standard voltage and a load, and to produce in the source of standard voltage a negative resistance characteristic which will neutralize the resistance of the control device so that the voltage across the load remains constant in spite of variations in the current passed through the control device.

A still further object of my invention is to connect a control device between a source of standard voltage and a load and to maintain a constant voltage across the load even when the voltage drop across the control device is a considerable fraction of the total voltage delivered by the standard voltage source.

A still further object of my invention is to supply a constant biasing current to a saturating reactor and to maintain the biasing current constant in spite of variations in input voltage, input frequency, and resistance of the biasing winding.

Another object of my invention is to connect a control device between the source of standard voltage and the load and to maintain a constant voltage across the load over a wide range of current through the control device, in both the positive and negative direction.

A still further object of my invention is to connect a control device between a source of standard voltage and a load and to maintain constant voltage across the load both when the standard voltage source is delivering current and when it is absorbing current, and to limit the maximum current which the standard voltage source will absorb.

Another object of my invention is to provide a stand-

2

ard voltage source whose output voltage can easily be changed in response to an external signal.

Other objects and a better understanding of my invention will be obtained by referring to the following specification and claims together with the accompanying drawing, in which:

Figure 1 shows an embodiment of my invention in which a standard voltage source comprising rectifiers regulated by impedance windings on saturable magnetic cores furnishes direct current to load terminals through a control device or resistance;

Figure 2 is a circuit diagram of a device similar to that of Figure 1, except that a single three-legged core structure is used in place of the two individual cores shown on Figure 1;

Figure 3 is the diagram of a biasing source which may be applied to Figures 1, 2, 5 and 6 and employing a ballast lamp;

Figure 4 is another alternate biasing source which may be applied to Figures 1, 2, 5 and 6 employing an alternating current voltage regulator of a different type than that shown in Figure 1;

Figure 5 is a modification of Figure 1, in which the same windings are used both for biasing and impedance windings, and in which provision is made for external adjustment of the output voltage by a separate signal; and

Figure 6 is still another modification of Figure 1, in which a center-tapped transformer is employed, and the biasing and regulating windings are combined.

Voltage and current regulators embodying the features of this invention are particularly suited for use as a source of standard voltage in a larger control system such as that shown and described in my U. S. patent application Serial No. 780,408, filed October 17, 1947, and in my U. S. patent application entitled "Regulated Rectifier," which is being filed concurrently with this application.

In a device of this type, a standard voltage is balanced against a load voltage, with a control device, or saturating winding, connected in series in the balancing circuit, so that whenever the load voltage is different from the standard voltage a circulating current flows through the control device or saturating winding and affects the operation of the main power source in such a way as to restore the load voltage to its standard value. It can readily be seen that whenever current flows through the control device or saturating winding, a difference in voltage will exist between the load voltage and the standard voltage. Therefore, if the standard voltage actually is constant at all times, the load voltage will not remain constant when a control current is flowing. In order to overcome this disadvantage, the standard voltage source employed in my application Serial No. 780,408 has an internal negative resistance characteristic which balances out the resistance of the saturating windings, so that a constant voltage can be maintained across the load even when appreciable current is flowing through the saturating windings.

To more fully explain the term "negative resistance characteristic," it can be stated that the output voltage of a voltage source having this characteristic will increase as the amount of load current delivered by it increases, and its voltage will decrease as its output current decreases. The voltage should preferably change at a uniform rate, so that a fixed value of negative resistance can be defined by the ratio of the change in output voltage to the change in output current.

By means of my present invention I am able to obtain a very uniform value of negative resistance over a wide range of load current, and am able to adjust the amount of negative resistance very readily over a wide range of resistance values. Furthermore, I am able to obtain very

high values of negative resistance without the loss of uniformity, so that the voltage drop across the control device may be large, perhaps greater than the load voltage, without loss of regulation.

Because of the high value of negative resistance obtainable with my present invention, it is adaptable to a wide variety of applications, such as the control of generator fields, and when used to control saturating reactors it may make possible considerable economies in the design of the reactors by relaxing limitations on the resistance of the saturating windings.

In my invention, I also overcome one of the common defects encountered in devices which employ a fixed biasing current to control a voltage. In devices of this type, it is usually necessary to compensate in some manner for changes in the resistance of the biasing windings resulting from changes in temperature. By my invention, I provide a constant current source for biasing these windings so that compensation for change in resistance is no longer necessary. This constant current biasing source is also unaffected by changes in line voltage and line frequency. The details of operation can be explained more fully by referring firstly to Figure 1.

The load current delivered by the arrangement of Figure 1 flows through the control device 26 to the load terminals 27 and 28. The control device may comprise saturating windings on one or more reactors, or a field winding of a generator or motor, or other type of direct current operated controlling element. In particular, the control device may regulate the output of another, perhaps larger, source of direct current which may supply current to the same load to which terminals 27 and 28 are connected. Thus, whenever the voltage across the load terminals drops, my direct current source will supply greatly increased load current to the load and at the same time actuate the control device as required to restore normal voltage across the load. Alternatively, the control device may be dispensed with, and the load may be taken directly across the terminals 61 and 28.

The direct current load terminals 27 and 28 are energized from the alternating current source 10 through rectifiers, 12, 13, 14 and 15 which comprise a full wave rectifier bridge having impedance windings 19 and 20 in two of the arms of the bridge, in series respectively with rectifiers 12 and 13. Impedance windings 19 and 20 have saturable magnetic cores 17 and 18. On core 17, windings 21 and 22 are used for biasing purposes and windings 23 and 24 on core 18 serve the same purpose. Windings 21 and 24 are connected in series with the load circuit and the load current flowing through them has a compounding effect, increasing the bias of the cores as the load increases.

A substantially constant biasing current is fed to windings 22 and 23 by rectifier bridge 32. The input voltage to rectifier bridge 32 is regulated by means of linear inductances 34 and 38 and saturable inductance 35. Because of the saturation of its core, the voltage across inductance 35 remains substantially constant over a wide range of voltage variations from source 10. Any slight tendency for the voltage across inductance 35 to increase with increasing voltage from source 10 can be corrected by properly locating the tap 36 on linear inductance 34. In fact, this tap can be positioned to provide a reverse characteristic, so that the voltage supplied to rectifier 32 diminishes as the voltage from source 10 increases. This characteristic may be useful in compensating for the effect of voltage variations from source 10 on the regulating circuit comprising rectifiers 12, 13, 14 and 15 and impedance windings 19 and 20.

Rectifier bridge 32 is energized from source 10 through linear inductance 38 and from tap 37 of linear inductance 34. By making the voltage drop across inductance 38 large in comparison with the voltage across rectifier 32, a constant current effect is obtained, so that the output current of rectifier 32 is substantially unaffected by the

resistance in its direct current circuit. Furthermore, by making inductance 38 the major impedance in this circuit, the effect of variations in the frequency of source 10 on the current output of rectifier 32 is substantially eliminated. The voltage drop across inductance 35 increases in direct proportion to the frequency of source 10, and at the same time the impedance of linear inductance 38 increases in direct proportion to the frequency of source 10. Consequently, the current passed through inductance 38 and rectifier 32 remains constant even though the frequency of source 10 may change considerably.

In order to prevent the ripple voltage from windings 22 and 23 from being fed back to rectifier 32, a filter choke 41 is inserted in series between rectifier 32 and saturating windings 22 and 23. The filtering is completed by the use of resistors 40 and 42 which effectively prevent ripple voltage from the biasing windings from reaching rectifier 32. Resistors 40 and 42 are preferably proportioned so that the direct current passed through them is negligible in comparison with the direct current output of rectifier 32, in order that the constant current characteristics of the circuit be preserved, and the effects of resistance changes resulting from temperature changes in windings 21, 22 and 23 may be eliminated. In order to adjust the output voltage, fine adjustment of the biasing current can be obtained by varying adjustable resistor 40 with the allowable limits. Further adjustment of the output voltage can be made with adjustable resistor 16..

Optimum regulation in the circuit of Figure 1 is obtained when the cores 17 and 18 (and 35) are of gapless construction and when the core material is grain oriented steel or one of the alloys having a substantially rectangular magnetization characteristic, such as Deltamax or Orthonik. The results described herein can be obtained with ordinary stamped transformer laminations, but larger cores are required than with the special core materials.

In the circuit of Figure 1, the windings are polarized so that the direct current magnetization produced by windings 19 and 20 is opposite to and no greater than that produced by windings 21, 22, 23 and 24. This circuit provides a very precise current transformer characteristic, so that the direct current ampere-turns produced by windings 19 and 20 will always be exactly equal to the direct current ampere-turns produced by windings 21, 22, 23 and 24.

The units 17 and 18 are preferably substantially identical, winding 19 having the same number of turns as winding 20, winding 21 having the same number of turns as winding 24, and winding 22 having the same number of turns as winding 23. If we represent the number of turns in winding 23 by the figure N_1 and the number of turns in winding 24 as N_2 , the turns in winding 20 as N_3 , and the currents through these windings as I_1 , I_2 and I_3 respectively, the equation which characterizes the operation of this circuit is $N_1I_1 + N_2I_2 = N_3I_3$.

Representing the resistance of the load resistor 16 as R_1 and the combined resistance of windings 24, 21, and 25 and element 26 as R_2 , the following equation also applies: $(I_3 - I_2)R_1 - I_2R_2 = E$, where E is the voltage across the terminals 27 and 28.

From this it will be seen that when $N_2 = N_3(1 + R_2/R_1)$ then $E = N_1R_1I_1/N_3$. When this relationship is established, E is therefore completely independent of I_2 which is the load current delivered to terminals 27 and 28. Furthermore, I_2 can be either positive or negative without affecting this relationship, although I_3 cannot be negative because of the limitations imposed on it by rectifiers. This limitation automatically limits the maximum negative value which I_2 can reach. The ability of a standard voltage source to operate with both positive and negative values of load current is a highly important feature in many cases, and is one of the advantages

of my invention. At the same time, there are many cases, particularly where the standard voltage source is used to control saturable reactors, where the amount of reverse current absorbed by the standard voltage source should be limited to prevent reverse saturation of the control reactors and a consequent abnormal operating condition. By my invention, I am able to limit the value of reverse current to almost any desired value simply by suitable adjustment of resistance 16 (R_1).

The load current delivered by the arrangement of Figure 1 flows through the filter inductance 25 and control element 26 to the load terminals 27 and 28. As previously mentioned, element 26 may comprise a control device, such as the field of a generator or a series of saturating windings on saturable reactors in a larger regulated rectifying arrangement, which also supplies load to terminals 27 and 28. On the other hand, the rectifying arrangement of Figure 1 can be used to supply load current directly to a load, in which case, resistance 26 is no longer in the circuit, and terminals 61 and 28 become the load terminals. Omission of the resistance 26 can readily be compensated by reducing the number of turns on the compounding windings 21 and 24.

The circuit arrangement shown in Figure 2 operates in essentially the same manner as that shown in Figure 1. The chief difference between the circuit of Figure 2 and that of Figure 1 is that the impedance windings 19 and 20 in Figure 2 are wound on a three-legged core structure, so that a single biasing winding 23 can readily embrace both of the flux paths for the two impedance windings 19 and 20 and a single compounding winding 24 likewise can embrace the flux paths of both of the impedance windings. The small arrows shown by each winding in Figure 2 indicate the direction of the direct current flux produced by that winding. It will be noted that the impedance windings 19 and 20 produce flux which is opposite to that produced by the biasing winding 23 and the compounding winding 24. This is the same relationship as explained in connection with Figure 1, and provides the type of operation outlined in connection with Figure 1.

The source of biasing current connected to terminals 30 and 31 in Figure 2 is represented simply by a battery 11 in series with an adjustable resistor 29 in place of the voltage regulated rectifier shown in Figure 1. Where a steady source of direct current is available, the biasing circuit of Figure 2 can readily be substituted for that of Figure 1. In order to compensate for the effect of voltage variations from source 10 on the current passed through impedance windings 19 and 20, I have found that the use of input voltage compensation is sometimes required. This is accomplished in Figure 2 by the use of rectifier 60 energized from transformer 62. The output current of rectifier 60 increases as the voltage of source 10 increases, thereby increasing the voltage drop across resistor 29 and consequently reducing the biasing current through winding 23 as the input voltage of source 10 increases. In this manner I am able to reduce the bias of the core 32 at a rate just sufficient to compensate for the effect of increasing input voltage on this circuit. As previously mentioned, the circuit of Figure 1 has a similar feature available in the use of tap 36 on inductance 23 which can be used to reduce the bias as the voltage from source 10 increases. When gapless cores of rectangular magnetization characteristics are used for cores 17, 18 and 32, this expedient may not always be necessary.

Two other alternative methods for obtaining biasing current are shown in Figures 3 and 4. In Figure 3, the rectifier bridge 32 energized from source 10 passes current through a ballast lamp 33 and adjustable resistor 29 to terminals 30 and 31 which are numbered to correspond with terminals 30 and 31 in the other figures. The ballast lamp maintains a constant biasing current in spite of the variations in the voltage of source 10,

and the reverse characteristic previously mentioned can also be obtained with this circuit. The ripple current produced across terminals 30 and 31 can be used to increase the temperature of the ballast lamp 33 as the voltage of source 10 increases to a sufficient degree to actually cause a reduction in bias current with an increase in input voltage. I have found that the application of the biasing arrangement shown in Figure 3 to the circuits shown in Figures 1, 2, 5 or 6 can be made to exhibit this characteristic sufficiently to permit the use of ordinary transformer laminations for the cores 17 and 18 or 32 in these figures.

The biasing circuit shown in Figure 4 employs a more conventional type of voltage regulator having a saturable core 39 energized from source 10 by primary winding 46, and having secondary winding 50 with capacitor 48 connected across it. Leakage shunts 51 separate the primary and secondary windings, and a compensating winding 47 together with tap 49 completes the output circuit which feeds power to rectifier bridge 32. This type of regulating circuit compensates for changes in the voltage of source 10 and delivers a constant voltage to terminals 30 and 31. A filter circuit comprising inductance 41, resistor 40 and capacitor 52 prevents ripple current from being fed back into terminals 30 and 31 where it would be rectified by rectifier 32 and affect the regulation.

It will be noted that a filter capacitor 52 is used in Figure 4 in place of the resistor 42 in Figure 1. These arrangements can be used interchangeably and the choice 30 is one primarily of design considerations. It should be pointed out that the regulating circuit of my invention will work equally well with either a high impedance or low impedance biasing source. The circuits shown in Figures 1 and 4 are essentially low impedance biasing sources, those of Figures 2 and 3 may be either high or low, whereas the circuit shown in Figure 5 has a high impedance biasing source, as the inductance 41 is connected directly in series with the biasing windings.

In the circuit of Figure 5, the same windings are used 40 for two purposes; that is, windings 19 and 20 are used both for impedance windings and biasing windings. They are provided with taps 43 and 44 to permit the use of different numbers of turns for the two functions, although 45 it will be apparent that the entire winding can be used for both purposes whenever proper circuit values are available.

In Figure 5, as in Figures 1 and 2, rectifier element 12 is in series with impedance winding 19, and rectifier element 13 is in series with impedance winding 20. However, the alternating current lead from source 10 goes directly to the junction between impedance windings 19 and 20 in Figure 5 instead of to the junction between rectifiers 12 and 13 in Figure 1. Actually, this is just a reversal of the relative positions of the rectifier and impedance winding in the series circuit and does not affect the operation.

The compounding windings 21 and 24 in Figure 5 are connected between the positive rectifier terminals and the load terminal 27, as in the Figures 1 and 2. The negative terminal 28 is connected directly to the negative rectifier terminal. In Figure 5, an adjustable resistor 45 is connected in series with the direct current output of the rectifier, this resistor may be added to any of the other circuits, and can be used to adjust the regulating characteristics of the circuit, in other words to adjust the positive resistance of the circuit to equal the negative resistance characteristic produced by the regulating arrangement.

When the biasing source has a high impedance as in 70 Figure 5, the voltage wave shape supplied to terminals 27 and 28 has considerably less alternating current component than when the biasing source has a low impedance, and the filter choke 25 shown in Figures 1 and 2 is omitted in Figure 5. However, in many cases, the deciding factor in determining whether or not the filter choke

25 can be omitted lies in the amount of ripple voltage produced from other sources across the load terminals 27 and 28 or produced in the control element 26. If appreciable ripple voltage appears from either of these two sources, it will generally be necessary to use a filter choke 25 in order to prevent rectification of the ripple voltage by the rectifiers 12, 13, 14 and 15.

In Figure 5, windings 53 and 54 have been added to the saturable cores 17 and 18 and connected to terminals 55 and 56. These terminals are to be energized from an external signal to modify the output voltage appearing across terminals 27 and 28, to provide remote manual control, load limiting characteristics, as in my prior application Serial No. 780,408, or other automatic control features such as those known and described in my patent application entitled "Regulated Rectifier" which is being filed concurrently with this application. In the circuit of Figure 6, a center-tapped transformer 59 is used and the compounding windings are combined with the biasing windings, but the essential operating features of the previous circuits are maintained. The half wave rectifier 12 is in series with impedance winding 19 and the half wave rectifier 13 is in series with impedance winding 20 as in Figures 1, 2 and 5.

The biasing windings 22 and 23 are provided with taps 57 and 58 by means of which the correct number of turns required for compounding are made available. The relative polarities of the windings are the same in Figure 6 as in the previous figures, and the operating features are the same. Figure 6 is similar to Figure 5 in that it shows a high impedance biasing source with the inductance 41 connected in series with the biasing windings.

In the circuits of Figures 5 and 6 where the same windings are used for two purposes, the circuit equations used for Figure 1 no longer strictly apply, but the corrections which have to be applied to make them properly describe the operation of Figures 5 and 6 are of a linear nature and do not destroy the essential properties of my invention.

Although I have described my invention as applied particularly to an application in which it serves as a standard voltage source to be used to operate a control device connected between it and load terminals for the purpose of maintaining constant voltage across the load terminals, it will be apparent that my invention may also be applied as a complete unit in itself for the provision of a regulated voltage or current. Furthermore, the various features shown and described in the several embodiments of my invention depicted herein are in general interchangeable between the various figures and numerous modifications known to those skilled in the art may be applied without departing from the spirit and scope of my invention as hereinafter claimed.

I claim as my invention:

1. Means for energizing a direct current control device comprising in combination, direct current load terminals connected to alternating current input terminals through rectifying means comprising a plurality of rectifying elements, a plurality of saturable magnetic flux paths, biasing winding means embracing said flux paths, means for supplying a substantially constant unidirectional current to said biasing winding means to magnetize said flux paths, a plurality of impedance windings, one embracing each of said flux paths, each of said impedance windings being connected in series with one of said rectifying elements, whereby said flux paths are demagnetized by current flowing through said rectifying elements, a resistance element energized with rectified current from said rectifying elements, compounding winding means embracing said flux paths, direct current circuit means extending between said resistance element and said load terminals and including the compounding winding means and said direct current control device in series, said compounding winding means being polarized to magnetize said flux paths

when current flows from said rectifying elements to said load terminals.

2. Means for energizing a direct current control device, comprising in combination, direct current load terminals connected to alternating current input terminals through rectifying means comprising a plurality of rectifying elements, a plurality of saturable magnetic flux paths, means for impressing on said flux paths a substantially constant unidirectional magnetizing force to magnetize said flux paths, a plurality of impedance windings, one embracing each of said flux paths, each of said impedance windings being connected in series with one of said rectifying elements, whereby said flux paths are demagnetized by current flowing through said rectifying elements, a resistance element energized with rectified current from said rectifying elements, compounding winding means embracing said flux paths, direct current circuit means extending between said resistance element and said load terminals and including the compounding winding means and said direct current control device in series, said compounding winding means being polarized to magnetize said flux paths when current flows from said rectifying elements to said load terminals.

3. A regulating arrangement having alternating current input terminals and direct current load terminals and comprising in combination, a saturable magnetic core structure having first, second and third core members, first and second substantially equal windings on said first and second core members respectively, third and fourth windings on the third core member, a plurality of rectifying elements, a resistance element, circuit means for supplying rectified current to said resistance element, said circuit means extending from said input terminals to said resistance element and including said rectifying elements and said first and second windings, one of said elements being in series with each of said two windings, whereby said windings are energized by alternate half-cycles of alternating current from said input terminals and impress additive unidirectional magnetizing forces across said third core member, means for supplying direct current to said third winding to produce in said third core member a magnetizing force opposite to said unidirectional magnetizing forces, and a direct current circuit extending from said resistance element to said load terminals through said fourth winding.

4. A regulating arrangement having alternating current input terminals and direct current load terminals and comprising in combination, a saturable magnetic core structure having first, second and third core members, first and second substantially equal windings on said first and second core members respectively, third and fourth windings on the third core member, a plurality of rectifying elements, a resistance element, circuit means for supplying rectified current to said resistance element, said circuit means extending from said input terminals to said resistance element and including said rectifying elements and said first and second windings, one of said rectifying elements being in series with each of said two windings whereby said windings are energized by alternate half-cycles of alternating current from said input terminals and impress additive unidirectional magnetizing forces across said third core member, means for supplying direct current to said third winding to produce in said third core member a magnetizing force opposite to said unidirectional magnetizing forces, and a direct current circuit extending from said resistance element to said load terminals through said fourth winding, said fourth winding being polarized to aid said third winding, the turns in said windings being in substantially the ratio

$$70 \quad N_4/N_1 = 1 + R_2/R_1$$

where N_4 is the number of turns in the fourth winding, N_1 the number of turns in each of the first two windings, R_1 is the resistance of said resistance element and R_2 is 75 the resistance of said direct current circuit.

5. A regulating arrangement having alternating current input terminals and direct current load terminals and comprising in combination, first and second substantially equal saturable magnetic cores, a first, a second and a third winding on each of said cores, corresponding windings on the two cores having a substantially equal number of turns, a plurality of rectifying elements, a resistance element, circuit means for supplying rectified current to said resistance element, said circuit means extending from said input terminals to said resistance element and including said rectifying elements and said first windings, one of said rectifying elements being in series with each of said first windings, whereby said first windings are energized by alternate half cycles of alternating current from said input terminals, means for supplying direct current to said second windings in series to produce in said cores magnetizing forces opposite to those produced by the first windings, and a direct current circuit extending from said resistance element to said load terminals through said third windings in series, said third windings being polarized to aid said second windings.

6. A regulating arrangement having alternating current input terminals and direct current load terminals and comprising in combination, first and second substantially equal saturable magnetic cores, a first, a second and a third winding on each of said cores, corresponding windings on the two cores having a substantially equal number of turns, a plurality of rectifying elements, a resistor, circuit means for supplying rectified current to said resistor, said circuit means extending from said input terminals to said resistor and including said rectifying elements and the said first windings, one of said rectifying elements being in series with each of said first windings, whereby said first windings are energized by alternate half cycles of alternating current from said input terminals, means for supplying direct current to the said second windings in series to produce in said cores magnetizing forces opposite to those produced by the rectified current through the first windings, and a direct current circuit extending from said resistor to said load terminals through said third windings in series, said third windings being polarized to aid said second windings, the turns in said first and third windings being in substantially the ratio $N_3/N_1=1+R_2/R_1$ where N_3 is the number of turns in the third winding, N_1 is the number of turns in the first winding, R_1 is the resistance of said resistor and R_2 is the resistance of said direct current circuit.

7. In combination with a rectifying arrangement having saturable magnetic core means, with impedance winding means, biasing winding means and compounding winding means thereon and having rectifying elements serially connected between alternating current input terminals and direct current load terminals through said impedance winding means and said compounding winding means, means for energizing said biasing winding means, comprising in combination, a saturable inductance element and a first linear inductance element connected in a series circuit energized from said input terminals, a second linear inductance element and a full-wave rectifier connected in series in a circuit substantially in parallel with the saturable inductance element, and a direct current circuit extending from said full-wave rectifier to said biasing winding means.

8. A regulating arrangement having alternating current input terminals and direct current load terminals and comprising in combination first rectifying means comprising a plurality of rectifying elements, magnetic core means having a plurality of saturable flux paths, biasing winding means embracing said flux paths, second rectifying means connected to said biasing winding means to supply current thereto and magnetize said flux paths, a plurality of impedance windings, one embracing each of said flux paths, one of said rectifying elements being in series with each of said impedance windings, a resistance

element energized with rectified current from said rectifying elements, compounding winding means embracing said flux paths, a direct current circuit extending from said resistance element to said load terminals through

- 5 said compounding winding means, a first alternating current circuit energized from said input terminals and comprising first and second substantially linear inductances in series with each other and with said second rectifying means, and a second alternating current circuit energized from said input terminals and comprising a saturable inductance in series with at least a portion of said first linear inductance.

9. In a circuit, the combination of a transformer having a saturable magnetic core, with first, second, and third windings thereon, a resistive circuit element, a rectifying element in series with the first winding and the resistive element, means for exciting the rectifying element, the resistive element and the first winding from an alternating current source, means for supplying direct current to the second winding, a direct current load circuit connected to said resistive element through said third winding, the turns in said first and third windings being in substantially the ratio $N_3/N_1=1+R_2/R_1$, where N_3 is the number of turns in the third winding, N_1 is the number of turns in the first winding, R_1 is the resistance of said resistive element, and R_2 is the resistance of said direct current circuit.

10. A regulating arrangement having alternating current input terminals and direct current load terminals, and comprising, in combination, saturable magnetic core means having first, second, and third winding means thereon, a rectifying element, a resistive circuit element, first circuit means for energizing the resistive circuit element from the input terminals through the first winding means and the rectifying element, means for supplying direct current to the second winding means, and a direct current load circuit extending from the resistive element to the load terminals through the third winding means, the first and third winding means having turns in the ratio $N_3/N_1=1+R_2/R_1$, where N_3 is the number of turns in the third winding, N_1 is the number of turns in the first winding, R_1 is the resistance of said resistive circuit element, and R_2 is the resistance of said direct current load circuit.

11. A regulating arrangement having alternating input terminals and direct current load terminals, and comprising, in combination, saturable magnetic core means having first and second magnetic paths, first winding means on said magnetic core means, said winding means having a first portion inductively related to said first flux path and having a second portion inductively related to said second flux path, a resistor, first and second rectifying elements, first circuit means for energizing the resistor from the input terminals through the first portion of the first winding means and the first rectifying element, second circuit means for energizing the resistance from the input terminals through the second portion of the first winding means and the second rectifying element, second winding means on said magnetic core means having turns inductively related to both of said flux paths, means for supplying a direct current to the second winding means, third winding means on the magnetic core means inductively related to both of said flux paths, and a direct current load circuit extending from the resistor to the load terminals through the third winding means, the turns on each of said flux paths being substantially in the ratio $N_3/N_1=1+R_2/R_1$, where N_3 is the number of turns in the third winding means, N_1 is the number of turns in the first winding means, R_1 is the resistance of said resistor, and R_2 is the resistance of said direct current circuit.

12. A regulating arrangement having alternating current input terminals and direct current load terminals and comprising in combination, saturable reactor means having impedance winding means and saturating winding means, means for impressing a substantially constant bias on said saturable reactor means, a resistor, first rectifying

means connected in series with said impedance winding means between the input terminals and the resistor whereby pulsating current is passed through said impedance winding means to magnetize said reactor means in opposition to said bias, and means for connecting said load terminals across said resistor through said saturating winding means whereby load current flowing through said saturating winding means magnetizes said reactor means in addition to said bias.

13. A regulating arrangement having alternating current input terminals and direct current load terminals and comprising in combination, saturable reactor means having impedance winding means and saturating winding means, means for impressing a substantially constant bias on said saturable reactor means, a resistor, first rectifying means connected in series with said impedance winding

means between the input terminals and the resistor, and means for connecting said load terminals across said resistor through said saturating winding means whereby load current flowing through said saturating winding means magnetizes said reactor means in addition to said bias.
